UNITED STATES PATENT OFFICE.

BALTZAR EMANUEL BOLLING, OF RACINE, WISCONSIN.

DIE-BLOCK.

1,394,247.

Specification of Letters Patent. Patented Oct. 18, 1921.

Application filed January 15, 1920. Serial No. 351,640.

To all whom it may concern:

Be it known that I, BALTZAR EMANUEL BOLLING, a citizen of the United States, and resident of Racine, in the county of Racine 5 and State of Wisconsin, have invented new and useful Improvements in Die-Blocks, of which the following is a description, reference being had to the accompanying drawings, which are a part of this specification.

10 This invention relates to improvements in die blocks more particularly adapted for use in die casting machines.

It is one of the objects of the present invention to provide a die block for making 15 what is commonly known as finished castings in which the molten metal is automatically forced into the die under pressure and when the metal has become hard the castings are automatically ejected from the die without 20 liability of breakage.

25 A further object of the invention is to provide a die block which is open at both ends to permit its easy attachment to a die table and adjustment with relation thereto in any direction.

30 A further object of the invention is to provide a die block in which it is not necessary to fasten the ejector plate to the plunger of the die casting machine.

35 A further object of the invention is to provide a die block to which the die may be easily removably connected and further, in which the die block has a large unobstructed opening to permit the positioning of a movable casting ejecting means part which may be easily interchanged to fit different forms 40 of castings.

45 A further object of the invention is to provide a die block which is of simple construction, is strong and durable and is well adapted for the purpose described.

With the above and other objects in view, the invention consists of the improved die block and its parts and combinations as set 50 forth in the claims, and all equivalents thereof.

In the accompanying drawing in which the same reference characters indicate the same parts in all of the views:

55 Figure 1 is a vertical sectional view of the improved die block shown attached to a portion of a die casting machine;

Fig. 2 is a perspective view of the die block;

Fig. 3 is a sectional view of portions shown 55 in Fig. 1, taken on line 3—3 of Fig. 1; and

Fig. 4 is a sectional detail view taken on line 4—4 of Fig. 1.

Referring to the drawing the numeral 5 indicates a portion of a die casting machine 60 in which 6 is the adjustably fixed head, 7 the vertical reciprocal head or table, 8 the ejector plunger and 9 the improved die block adjustably mounted on the reciprocal head or table 7.

The die block 9 is of rectangular 65 form and has a comparatively large rectangular opening 10 extending vertically therethrough and which opening forms opposite shoulders 11 extending inwardly from the lower opposite end portions of the block. 70

The opposite end portions are also provided with outwardly extending slotted ears 12 for receiving bolts 13 which attach the block to the table. To permit adjusting the die block 75 horizontally in all directions the table or head 7 is provided with T-shaped slots 14 to receive slotted bolt members 15. These

members 15 are also of T-shape to fit the slots 14 and the headed ends of said bolts 13 fit in and extend through the slots 15' of 80 said members. Said slots 15' extend at right angles to the slots 14 to permit the lateral movement of bolts therein, and as the slots 14 permit adjustment at right angles thereto, the die block may be easily adjusted as desired. Nuts 16 threaded on the upper end 85

portions of the bolts 13 and bearing on the upper surfaces of the slotted ears 12 clamp the parts in adjusted position.

The die block 9 at each corner is provided 90 with a vertically extending opening 17 to receive bolts 18 which thread into the corner portions of the lower die portion 19 and fasten said die portion to the die block. The lower end portions 17' of the openings 95 17 are enlarged to accommodate the heads of the bolts 18.

A rectangular space 20 which coincides approximately with the opening 10 of the die block is formed in the reciprocal head or 100 table 7 to receive the ejector plunger 8, the stem 7' of which extends through the head 7. Resting on top of the ejector plunger 8 are ejector plates 21 having upwardly extending

ejector pins 22 and stop pins 23 which extend through the die part 19. The die pins 22 are of small diameter and terminate at the upper surface of the casting recess 19' of the die 5 part in position to push the casting out of the die part 19 when the said die part is moved downwardly by the reciprocal head 7 and away from the upper fixed die part 24. The stop pins 23 terminate at the upper face 10 of the die part and engage the lower surface of the upper die part 24 to properly position the upper ends of the ejector pins 22 with respect to the die recess and provide an exact register therewith.

15 When the die casting is provided with an opening or core, a core block 25 is mounted in one of the die blocks in the manner shown and preferably in the lower die part so that the casting will be pushed off the core block 20 by the ejector pins at the same time the casting is pushed out of the lower die.

The upper die part 24 is mounted on a die block and the die block is mounted on the adjustably fixed head 6 in substantially the 25 same manner as the lower die part and die block and the same reference characters will apply.

The molten metal is forced into the casting recesses of the die parts when said parts 30 are in closed position through the opening 25' formed between the two die parts.

From the foregoing description it will be seen that the die block is of very simple construction and well adapted for the purpose 35 described.

What I claim as my invention is:

1. In combination with a die casting machine having T-shaped slots, of a die block therefor, consisting of a block member of 40 rectangular form having a comparatively large ejector opening extending vertically therethrough and also having projecting apertured ears to receive bolts for attachment to the T-shaped slots of the machine and also 45 having bolt openings extending vertically through the block for attaching a die part to the block.

2. In combination with a die casting machine having T-shaped slots and a central 50 recess, of a die block therefor, consisting of a block member of rectangular form having a comparatively large rectangular opening extending vertically therethrough and also 55 having projecting slotted ears on opposite side portions to receive bolts for attachment to the T-shaped slots of the machine, said block member also having bolt openings extending vertically through portions of the block adjacent the corners for receiving bolts 60 for attaching a die part to the block.

3. In combination, a die casting machine 65 having a member provided with T-shaped slots and a central recess, a block member having a comparatively large opening extending vertically therethrough and also

having projecting apertured ears and vertically extending bolt openings, bolts having their headed ends within the T-shaped slots and extending through the apertured ears for adjustably connecting the block to the 70 machine member, a die part mounted on the block member, bolts extending through the bolt opening of the block member and threaded into the die part, and an ejector member positioned within the large opening 75 of the block member.

4. In combination, a die casting machine having a fixed head and a movable head, said movable head having T-shaped slots and a central recess, a block member having a comparatively large opening extending 80 vertically therethrough and also having projecting apertured ears and vertically extending bolt openings, bolts having their headed ends within the T-shaped slots and extending through the apertured ears for adjustably connecting the block to the machine member, slotted bolt members interposed between the bolt heads and the slotted portions of the movable head and through which the 85 bolts extend, a die part mounted on the block member and having a plurality of ejector pin and other openings extending vertically therethrough, and an ejector plunger positioned in the movable head recess and having a plurality of ejector pins which extend into the pin openings of the die part and also having stop pins which extend through the other openings of the die part.

5. In combination, a die casting machine having a fixed head and a movable head, said movable head having T-shaped slots and a central recess, a block member having a comparatively large opening extending 90 vertically therethrough and also having projecting apertured ears and vertically extending bolt openings, bolts having their headed ends within the T-shaped slots and extending through the apertured ears for adjustably connecting the block to the machine member, slotted bolt members interposed between the bolt heads and the slotted portions of the movable head and through which the 95 bolts extend, said bolt members being of T-shape to fit the T-shaped slots of the movable 100 head, the slots of said bolt members extending at right angles to the slots of the movable head, a die part mounted on the block member and having a plurality of ejector pin and other openings extending vertically 105 therethrough, and an ejector plunger positioned in the movable head recess and having a plurality of ejector pins which extend into the pin openings of the die part and also having stop pins which extend through the 110 other openings of the die part.

6. A block member for a die casting machine, consisting of a rectangular block having a central rectangular vertically extending 115 ejector opening of comparatively large 120

size and also having opposite end slotted ears and vertically extending corner bolt openings, said central opening forming opposite inwardly extending ejector supporting shoulders.

7. In combination, a die casting machine comprising a support for a die block having slots therein, said slots being T shaped in cross section, bolt members shaped to fit said 10 slots and movable therein, said members

having slots T shaped in cross section and extending transversely of said first named slots, bolts for attachment of a die block, the heads of said bolts seated in the slots of said members whereby a die block attached by 15 said bolts may be adjusted in all directions in the plane of the support.

In testimony whereof I affix my signature.

BALTZAR EMANUEL BOLLING.
